UNITED STATES PATENT OFFICE.

FRANK L. DYER, OF MONTCLAIR, NEW JERSEY.

SPARK-PLUG.

1,324,885.

Specification of Letters Patent.

Patented Dec. 16, 1919.

Application filed April 27, 1917. Serial No. 164,849.

To all whom it may concern:

Be it known that I, FRANK L. DYER, a citizen of the United States, residing at Montclair, in the county of Essex, State of New Jersey, have invented certain new and useful Improvements in Spark-Plugs, of which the following is a specification.

My invention relates to various new and useful improvements in spark plugs and my object is to improve the construction and facilitate the manufacture of the same. The plug is preferably of the type in which the core within the porcelain member of the plug is a composite core composed of an upper iron or steel section and a lower section of a nickel alloy capable of more effectively withstanding the high temperatures. The joint between the two sections is located within the porcelain member of the plug. The lower nickel alloy section may itself directly constitute one of the electrodes of the plug or it may carry one or more separate stationary or movable electrodes. In the make-up of spark plugs using composite cores it is sometimes the practice to hold the core in position by means of a packing of asbestos or similar material but with this construction the core is not held very firmly and is likely to become dislodged and there is always a possibility of leakage around the core due to the high gas pressures. With other types of spark plugs using composite cores it is the practice to cement the upper portion of the core in place within the porcelain and although with this construction the core will be very rigidly secured within the porcelain with a gas-tight joint, there is danger of the porcelain cracking under the effect of heat due to the difference in the co-efficients of expansion of the core and the porcelain. With my improved spark plug using a composite core I secure the core very firmly and rigidly in place, always with a gas-tight joint, and at the same time reduce to a large extent the likelihood of the porcelain cracking, no matter to what extent the core may expand or contract longitudinally with reference to the porcelain. Furthermore, in the manufacture of the spark plug I provide substantial economies since I do away entirely with the need of separately packing or cementing the core in position.

Broadly, my invention consists of a spark plug in which the core is anchored to the porcelain at an intermediate point in the

bore thereof. This is effected by localizing a very intense heat at an intermediate section of the core or in a body of hard spelter between the two sections of the core whereby the metal will soften and flow diametrically so as to form a tight joint with the porcelain thus anchoring the core at an intermediate point within the porcelain with a gas-tight joint and permitting the core on either side of the joint to expand independently of the porcelain to thereby remove any possibility of cracking the same due to uneven expansion.

While I prefer to make use of my present invention in connection with spark plugs having composite cores as explained, this is not strictly necessary because the invention may be carried out in connection with spark plugs having continuous one-piece cores, the latter being reduced at an intermediate portion so as to localize the heat, permitting the metal to flow at that point and forming a mechanically strong anchoring joint with the porcelain, all as I will more fully hereinafter describe and claim.

In order that the invention may be better understood, attention is directed to the accompanying drawing forming part of this specification, and in which—

Figure 1 is a sectional view of a spark plug embodying my present improvements of the type in which the inner electrode is in the form of a small fan presenting a number of radiating points;

Fig. 2 a similar view showing the parts ready to be assembled before the anchoring joint is formed in the composite core;

Fig. 3 a similar view showing a modification in which a speltering action is performed to produce the joint instead of a weld as with Figs. 1 and 2.

In the above views corresponding parts are represented by the same reference numerals.

It is to be particularly noted that in all of these views the space between the bore of the porcelain and the core is very considerably exaggerated. In actual practice the core will fit the porcelain with a fairly easy fit, not allowing any substantial play but providing sufficient space in which the upset metal may flow to form the anchoring joint. 1 is the metal shell of the plug screwed into the engine cylinder and having a gasket 2 holding the porcelain 3 in place in the usual way. This porcelain is provided with a

bore which may be of any suitable construction. As shown, the upper part of the bore 4 is of slightly larger diameter than its lower part 5, so as thereby to form a shoulder between the two parts. Carried within the porcelain is a composite core composed of a larger part 6 made of iron or steel and a smaller lower part 7 made of a nickel alloy. Between the two parts is a joint 8 which 10 holds the parts rigidly together as one piece and at the same time anchors the core tightly in position within the porcelain with a mechanically strong gastight joint. This joint is formed by electrically welding the two 15 parts 6 and 7 together, as shown in Fig. 2. Here it will be observed that the abutting ends of the sections 6 and 7 are somewhat reduced in diameter so as to localize the current and concentrate the heat at an intermediate point. By applying current to the 20 sections 6 and 7 from the transformer 9 the reduced portion of the core will be heated to the welding temperature and by then applying pressure to the two clamps 10, 10, 25 forcing them inwardly, the welded metal will be upset, forming a tight joint between the core and the porcelain and at the same time practically consolidating the two sections of the core. It will be understood 30 that in order to reduce the possibility of cracking the porcelain during the welding operation, the porcelain may be first heated and be in a heated state during the welding operation. Of course it will be understood 35 that instead of making the core composite as shown, it may be made of a single piece of metal which is reduced in diameter at an intermediate point so as to localize the current and thus bring about the welding 40 of the metal to form the joint between the core and the porcelain.

In Fig. 3 the operation is the same as above described except that a small ball 11 of spelter is used, preferably melting at a 45 high temperature (slightly below the welding point of the core) and offering sufficient resistance to the current to produce the heating effect.

If desired the section 6 may carry an in-

tegral cap 12 which fits over the upper end 50 of the porcelain so as to give the desired finish to the plug and between said cap and the upper end of the porcelain may be interposed an asbestos packing 13 which will prevent any possibility of leakage of gas 55 and at the same time will yield slightly when the core expands with respect to the porcelain. Above the cap 12 is shown a nut 14 for making the usual connection electrically to the plug. 60

Having now described my invention, what I claim as new therein and desire to secure by Letters Patent is as follows:

1. An improved spark plug in which the core is provided with a welded joint intermediate of its length, locking the core to the continuous one-piece porcelain. 65

2. An improved spark plug using a composite core in which the two sections of the core are united together by a welded joint 70 which also fastens the core to the continuous one-piece porcelain intermediate of its length, substantially as set forth.

3. In a spark plug, the combination with the continuous one-piece porcelain member 75 thereof, of a core therein having an intermediate welded joint locking the same to the porcelain.

4. In a spark plug, the combination with the continuous one-piece porcelain member 80 thereof, of a core therein having an intermediate welded joint locking the same to the porcelain, and an integral cap carried by the core and fitting the end of the porcelain.

5. In a spark plug, the combination with the continuous one-piece porcelain member 85 thereof, of a core therein having an intermediate welded joint locking the same to the porcelain, an integral cap carried by the core and fitting the end of the porcelain, and 90 an elastic packing interposed between the cap and the end of the porcelain.

This specification signed and witnessed this twenty-sixth day of April, 1917.

FRANK L. DYER.
